UNITED STATES PATENT OFFICE

CLEMENT R. UHL, OF TOLEDO, OHIO, ASSIGNOR TO THE TOLEDO METAL FURNITURE COMPANY, OF TOLEDO, OHIO, A CORPORATION OF OHIO

CASTER

Application filed April 22, 1931. Serial No. 531,947.

This invention relates to casters or swivel wheels of the type commonly used on furniture, small trucks and similar articles, and has for its object the provision of simple and efficient means for attaching the wheel and its bearing pin to the fork member of a 5 caster, so as to enable them to be easily and quickly assembled and also separated to facilitate repair or replacement of the wheel 10 and pin, or either, and also cleaning and freeing the pin of accumulated matter, such, for instance, as threads which interfere with the free running of the wheel.

The invention is fully described in the 15 following specification, and while in its broader aspect it is capable of embodiment in different forms, one embodiment thereof is illustrated in the accompanying drawing, in which—

20 Figure 1 is a side elevation of a caster embodying the invention attached to a furniture leg, and Fig. 2 is a section on the line 2—2 in Fig. 1.

Referring to the drawing, 1 designates the 25 fork member of the caster, 2 the wheel, and 3 the pivot or bearing pin, which is mounted at its ends in the leg portions of the fork and held thereby against turning and forms a bearing intermediate the fork legs on 30 which the wheel turns, as is customary in the art.

The fork member is provided in the lower 35 end of each leg with a vertical or upwardly extending notch 4 for receiving either end of the pin 3 and is preferably of a length considerably greater than the diameter of the leg-engaging end portions of the pin, and of a width substantially the same as the pin diameter, as shown.

40 The pin 3, when in operative position, has bearings against both the end and side walls of the notches, and one end of the pin is squared as at 5, or at least provided with two opposed flat surfaces for coaction with the 45 side walls of the notch in which disposed, to prevent turning of the pin relative to the fork. The edges of the mouth portions of the notches 4 are preferably rounded to facilitate entry of the pin ends therein. The 50 pin 3 is longer than the outside width of the

fork 1 to cause its ends to project slightly from the fork sides when centered therein.

A spring finger 6 is fixed at one end to the outer side of each leg of the fork 1, in the present instance, near its top, by a rivet 55 7, or other suitable fastening means, and projects downwardly therefrom over or in covering relation to the respective notch 4, with its free end terminating substantially at the bottom of the leg, or lower end of the notch. 60

An outwardly bulge or offset 8 is provided in each finger 6 to form a recess for receiving the adjacent projecting end of the pin 3 when in operative position in the fork. The free end of each finger 6 is also outwardly offset 65 from the respective leg, as indicated at 9, to facilitate entry of the pin into the mouth portions of the notches 4 between the ends of the two spring-fingers without disturbing the normal positions of the fingers, as shown by 70 dotted lines in Fig. 2. The reentrant portions 10 of the fingers 6, which are disposed between the offset portions 8 and 9 of the fingers, coact with the respective ends of the pin 3 to normally retain the pin in the inner 75 end portions of the notches 4, and said portions 10 have the upper and lower ends of their inner sides rounded, or of other suitable form, to facilitate the ends of the pin being forced past the same when sufficient 80 pressure is applied thereto upon an insertion into or withdrawal of the pin from the fork.

It is apparent that a wheel and its pin may be easily and quickly placed in assembled position with respect to the fork by inserting the roller within the fork with the pin ends seating in the mouth portions of the notches 4, and that by then exerting sufficient inward pressure against the wheel the pin is forced past the reentrant portions 10 of the spring-finger 6 and into the recesses formed by the offset portions 8 of said fingers, in which position the end portions of the pin have a bearing against the inner ends of the notches. It is also apparent that the roller and its pin 90 may be easily and quickly removed from the fork for the purpose of cleaning, repair or replacement, by merely exerting a sufficient downward pull on the wheel relative to the 95 fork to spring the ends of the pin past the 100

shouldered or reentrant portions 10 of the fingers.

I wish it understood that my invention is not limited to any specific construction, arrangement or form of the parts, as it is capable of numerous modifications and changes without departing from the spirit of the claims.

Having thus described my invention, what I claim as new and desire to secure by United States Letters Patent is:

1. In a caster, a fork having upwardly extending bearing notches in the lower ends of its legs, a bearing pin mounted at its ends in said notches and removable therefrom lengthwise of the notches and transversely of the pin axis, said pin being longer than the width of the fork, a wheel rotatably mounted on the pin within the fork, and a spring-finger fixed at one end to the outer side of each fork leg and having its free end projecting downwardly over the respective notch and terminating near the end thereof, each of said fingers having an inturned shoulder portion without the assembled position of the pin to coact with the pin ends and yieldingly retain the pin in operative position at the inner ends of the notches.
2. In a caster, a fork having a downwardly extending notch in the free end of each leg, a pivot pin mounted at its ends in said notches and removable therefrom lengthwise of the notches and transversely to the pin axis, the ends of the pin projecting beyond the sides of the fork and one of said ends being other than round to prevent its turning in the fork, a wheel mounted on the pin within the fork, and a spring-finger fixed to the outer side of each leg of the fork and having its free end projecting downwardly over the respective notch and terminating substantially at the end of the notch, said springs having coaction with the respective ends of the pin, and having inwardly shouldered portions in spaced relation to the inner and outer ends of the notches which resist both an insertion of the pin into the inner end portions of the notches and a removal of the pin therefrom.

In testimony whereof I have hereunto signed my name to this specification,

CLEMENT R. UHL.
